UNITED STATES PATENT OFFICE.

MICHAEL J. KOCH AND HARRY B. BOOSE, OF PITTSBURGH, PENNSYLVANIA.

PRINTING APPARATUS.

Application filed November 15, 1921. Serial No. 515,252.

To all whom it may concern:

Be it known that we, MICHAEL J. KOCH and HARRY B. BOOSE, both citizens of the United States, and residents of the city of Pittsburgh, in the county of Allegheny and State of Pennsylvania, have invented a new and useful Improvement in Printing Apparatus, of which the following is a full, clear, and exact description.

10 The present invention relates broadly to photography, and more particularly to printing apparatus for use in connection therewith.

15 At the present time it is customary to print from negatives in a plurality of different ways by the use both of rotating and stationary printing devices. Where rotating drums have been utilized for carrying the negatives, they have either not been

20 internally divided to produce a series of separate light compartments, or they have been polygonal in cross section. In the first case, it is extremely difficult to provide means for varying the duration of the printing period as required by negatives having

25 different characteristics. In the second case, it is extremely difficult to hold the paper and films in position by means of an endless belt, as such belt tends to arch off

30 the flat portions of the drum by reason of the high points on the drum.

The present invention has for its object the provision of a printing apparatus of the rotary type adapted to overcome the objections which exist with apparatus of this general type at present in use, and to facilitate the operation thereof and increase the output.

40 The present invention also provides in an apparatus of this type a comparison device comprising representative negatives and an easily operable means for varying the duration of the printing period in accordance with the characteristics of any particular film as compared with said comparison device.

45 The foregoing and other objects of the present invention, together with their attendant advantages, will be apparent as the invention becomes better understood by reference

55 to the accompanying specification and drawings forming a part thereof, it being premised that changes may be made in the details of construction and manner of operation without departing from the scope of our invention or our broader claims.

60 In the drawings:

65 Figure 1 is a top plan view of an apparatus constructed in accordance with the present invention;

70 Figure 2 is an end view of such apparatus illustrating the driving mechanism;

75 Figure 3 is an end view of the opposite end of the apparatus;

80 Figure 4 is a vertical sectional view on the line IV—IV of Figure 1;

85 Figure 5 is a sectional view on the line V—V of Figure 4 looking in the direction of the arrows;

90 Figure 6 is a detail top plan view of a portion of the rotating drum;

95 Figure 7 is a detail view of a portion of the timing mechanism;

100 Figure 8 is a perspective view of the timing contact;

105 Figure 9 is a diagrammatic view illustrating the electrical connections for the present apparatus;

110 Figure 10 is a diagrammatic end elevation of a slightly modified form of apparatus;

115 Figure 11 is a detail perspective view of a portion of the perforating device used in the apparatus illustrated in Figure 10;

120 Figure 12 is a view corresponding to Figure 10, illustrating a still further modification; and

125 Figure 13 is a detail top plan view of a portion of the modified rotating drum used with the apparatus illustrated either in Figure 10 or 12.

As illustrated in the drawings, an apparatus constructed in accordance with the present invention may comprise any desired supporting frame 2, carrying a transversely extending shaft 3 for supporting the rotating printing drum 4. This printing drum has preferably a uniformly curved periphery provided with a series of printing openings 5 extending therethrough, preferably

adjacent one end of the drum. The interior of the drum is divided into a series of separate light compartments 6 by partitions 7 projecting radially of the drum from the hub 8 and joined to the periphery thereof at suitable points intermediate the printing openings 5. Co-operating with each of the openings 5 is a curved transparent closure 9 secured in suitable depressions in the drum and having a curvature conforming to the curvature of the periphery of said drum.

Suitably supported within each of the compartments 6 is a non-actinic light source 10 and also an actinic light source 11. The actinic light source, which may comprise any desired number of printing lights arranged to give efficient light distribution, is preferably mounted in each compartment on a base 12. These bases are radially adjustable to vary the printing intensity of the light source by means of a slot and clamping bolt construction 13 cooperating with each of the bases.

Secured to one end of the shaft 3 is a worm wheel 14 adapted to be driven by a worm 15 on the upwardly extending drive shaft 16. The lower end of the drive shaft 16 carries a clutch member 17 adapted to engage a similarly shaped clutch member on one face of the worm wheel 18. The worm wheel 18 is in turn driven by a worm 19 on the shaft 20 of an electric motor 21. The clutch member 17 is operatively connected to the shaft 20 by a pin and slot connection 22, whereby it may be moved longitudinally of said shaft to disengage it from the worm wheel 18. This movement against the action of a spring 23 which is normally effective for holding the clutch members in operative engagement, is produced by a lever 24 pivotally secured to the frame 2 and operated by a link 25 secured to the foot treadle 26. The foot treadle is located adjacent the front of the machine in such manner that an operator may keep one foot continuously thereon. Cooperating with the foot treadle 26 is a switch 27 adapted to be thrown to inoperative position each time the foot treadle 26 is depressed, as will be hereinafter more fully pointed out.

Each of the transparent closures 9 has co-operating therewith mats 28 adjustably carried on suitable rods 29, as is common in this art. For positioning the negatives and the printing paper on the closure, there may be provided a series of resilient stops 30, each having one end secured to the drum 4, as indicated at 31, and thence bent upwardly to provide positioning shoulders 32, as clearly shown in Figure 5. The opposite ends of the stops extend downwardly through suitable openings in the drum and thence outwardly to provide holding lugs 33.

Passing around a substantial portion of

the periphery of the drum 4 is an endless belt 34 of any desired flexible material. This belt passes around idler rolls 35 and 36 carried by the frame 2 with their peripheries adjacent the periphery of the drum 4, and thence around a second set of idler rolls 37. The roll 35 is preferably carried by arms 38 having a pivotal connection 39 with the frame 2 and extending forwardly therefrom whereby the roller 35 may have a slight upward movement with respect to the drum 4 in case an operator gets his fingers caught therebetween. One of the rolls 37 is also preferably similarly carried by arms 40, one of which is subject to the action of a tension spring 41, the opposite end of which is attached to the frame 2 for maintaining tension on a belt 34. This belt is preferably slightly wider than the length of the closures 9 and passes around the drum in such manner as to cooperate therewith. As each set of stops 30 move into engagement with the belt 34, they are pressed downwardly substantially flush with the periphery of the drum 4 and thereafter the belt maintains the negatives and printing paper in proper position.

Extending any desired distance around the periphery of the drum 4 at one side of the belt 34, is a curved timing contact 42, shown in perspective in Figure 8. The contact 42 is mounted on an insulating backing 43 which is secured in any desired manner to the frame 2. At its upper end, the contact carries a wear strip 44 adapted to initially engage adjustable contacts 45 projecting upwardly from the drum and produce a snap action thereto. The contacts 45 may be made from any desired flexible material and are secured to sliding blocks 46 movable longitudinally on conducting slide bars 47. The timing contact 42 has its outer edge, as viewed in Figure 1, extending in a straight line, while its inner edge is cut on an oblique line. By reason of this construction, it will be apparent from an inspection more particularly of Figure 9, that as the contacts 45 are moved outwardly along the contact bars 47 they are brought into such a position that they will remain in engagement with the contact 42 for substantially the entire length thereof. As the contacts 45 are moved inwardly, however, the periods during which such engagement will be maintained are progressively decreased. Advantage is taken of this construction for automatically varying the duration of the printing period as may be found necessary.

Carried by the frame 38, which carries the idler roll 35, is a comparison device comprising a lamp-box 48 having an open front face covered by a comparison chart. This chart may comprise a series of negatives *a*, *b*, *c*, *d*, *e* and *f*, having different characteristics and requiring, respectively, successively longer

printing periods. The periphery of the drum underlying this comparison device, may be provided with a series of lines 50, corresponding to the divisions between the 5 comparison films of the chart. By reason of this construction, an operator may place a negative in position on one of the transparent closures 9, compare the same with this comparison chart, set the contact 45 10 accordingly and the picture will be properly printed. The non-actinic light sources 10 in each of the compartments 6, permit this observation of the negative.

Cooperating with the entire apparatus is 15 a table 51 having transparent upper and lower inserts 52 to permit an operator to look therethrough and observe whether or not the finished prints are being removed from the endless belt 34 by the doctor blade 20 53 and delivered to the receptacle 54 provided for this purpose. In the table between the inserts 52 is a non-actinic light source 55. If desired, the negatives may be placed over the upper insert 52 and observed before 25 being placed on the drum 4.

In order to show more clearly the wiring of the present apparatus, reference will be had to Figure 9 in which there are disclosed main line wires L and L'. These wires deliver current to the apparatus through a main switch 56. In the present machine this switch is adapted to be manually opened and closed by an operating handle 57 having a suitable connection 58 with the operating 30 handle 59 for the switch, as shown in Figure 3. With the switch in closed position, current will be supplied to the motor 21 through the wires 60, and to conducting rings 61 and 62 through the brushes 63 and 40 64 connected to the wires 65 and 66. These rings 61 and 62 are mounted concentrically with the shaft 3 on one end of the drum, as apparent from Figure 3, and the brushes 63 and 64 are carried by the frame 2. Current 45 will also be supplied to the non-actinic light source 55 in the table 51 and to the non-actinic light source 67 in the comparison lamp-housing 48. From the ring 61 current 50 will flow through wire 68 to one side of each of the non-actinic light sources 10 within the compartments 6. The opposite sides of these lamps are in connection with the ring 62 through wire 69, all of the light sources 10 being connected in parallel. The wire 69 55 also has a branch connection 70 leading to one side of each of the actinic light sources 11 within the compartments 6. The opposite sides of these light sources are connected by wires 71 to independent fixed conducting pivots 72. Each of these pivots carries a frictionally mounted triangularly shaped conducting blade 73. Referring to Figure 3, as the drum rotates in the direction of the arrow, the blades 73 will be brought into 60 engagement with a pin 74 projecting in-

wardly from the frame 2. This will swing the same about the pivots 72 and out of engagement with the spring contacts 75 electrically connected with each of the conducting bars 47. This operation occurs just 70 prior to the time that a transparent closure 9 is brought into position for the placing of a negative thereon. Therefore, at the time the contacts 45 are adjusted on the bars 47, these bars are out of electrical connection 75 and the operator is not subjected to a shock. Continued rotation of the drum will, however, bring the blades 73 into engagement with a fixed pin 76 projecting inwardly from the frame 2. This will swing 80 the blades in the opposite direction into engagement with the contacts 75, thereby placing the bars 47 in electrical connection with one side of the actinic light sources 11. At substantially this same time, but preferably slightly thereafter, the contacts 45, so connected, engage the wear bar 44, and thence snap into engagement with the timing contact 42. This contact is connected by a wire 77 with the opposite side of the source 90 of current, whereby the circuit is completed to such of the actinic light sources as have their contacts 45 in engagement with the timing contact. This will subject the negatives and printing paper to a printing light 95 for variable periods of time depending upon the setting of the contacts 45. When it is desired to temporarily stop rotation of the drum, the foot treadle 26 is depressed. This will operate the foot switch 24 throwing 100 it to its inoperative position, as illustrated in Figure 9, whereby the actinic light sources will be cut out of circuit. As soon as the foot treadle is released, the circuit will again be established to these light sources and the 105 drum will continue its rotation.

It will be apparent from the foregoing that there is provided convenient means for rapidly operating adjustable contacts, as shown necessary by a comparison of the films 110 being used with the comparison chart.

In certain cases, it may be desired to print on a continuous strip of paper. Where such is the case, the printing drum 104 may have in equally spaced lines on its periphery a 115 series of perforating pins p adapted to pass under the endless belt 134 and perforate the printing paper between successive pictures. The printing paper may be fed from a suitable source of supply and be wound onto a roll positively driven in any desired manner from the drum shaft 103', otherwise, the apparatus may be constructed exactly in accordance with the construction hereinbefore described, with the exception that each 120 of the transparent closures 109 may have cooperating therewith holding clips 110 for maintaining negatives in fixed position. It will be apparent that with this type of apparatus a series of pictures could be printed 125 130

from each negative and it is therefore desirable to hold the negative fixedly in position. If desired, strips of adhesive tape may be effectively substituted for the clips 110.

5 In Figure 12 there is illustrated a still further modification in which the drum 104 has no perforating points on its periphery but is adapted to deliver the paper P between cutting rolls 111 driven in any desired manner from the shaft 103 and provided with a cut-off blade 112.

The advantages of the present invention arise from the provision of means for readily comparing the films being used with a 15 comparison chart and varying the printing periods accordingly.

Further advantages arise from the means for preventing injury to the operator during use of the machine and from the ease 20 of operation thereof.

We claim:

1. In a printing apparatus, a rotating drum having a uniformly curved periphery, means dividing the drum into a series of 25 light compartments each having an exposure opening, an independently regulable light source for each compartment, and a flexible belt extending partly around the periphery of said drum and cooperating with said exposure openings, substantially as described.

2. In a printing apparatus, a rotating drum having a uniformly curved periphery, means dividing said drum into a series 35 of light compartments each compartment having an exposure opening, an independently regulable light source for each compartment, and an endless belt of flexible material extending partly around the periphery of said drum in contact therewith, substantially as described.

3. In a printing apparatus, a rotating drum having a uniformly curved periphery, means dividing the drum into a series 45 of light compartments each having an exposure opening, an independently regulable light source for each compartment, a flexible belt extending partly around the periphery of said drum and cooperating with said exposure openings, and means for maintaining said belt under tension, substantially as described.

4. In a printing apparatus, a rotating drum having a uniformly curved periphery, means dividing said drum into a series 55 of light compartments each having an exposure opening, an independently regulable light source for each compartment, an endless belt of flexible material extending partly around the periphery of said drum in contact therewith, and means for maintaining said belt under tension, substantially as described.

5. In a printing apparatus, a rotating 60 drum having a uniformly curved periph-

ery, means dividing said drum into a series of light compartments, each having an exposure opening, a curved transparent closure for each opening, an independently controlled light source for each compartment, and a flexible belt extending partly around the periphery of said drum in contact therewith and with said closures, substantially as described. 70

6. In a printing apparatus, a rotating 75 drum, means dividing said drum into a series of light compartments, each having an exposure opening, a light source for each compartment, a flexible belt extending partly around the periphery of said drum for cooperating with said exposure openings, and stops for each of said openings, said stops being adapted to move inwardly when engaged by said belt, substantially as described. 80

7. In a printing apparatus, a rotating drum having exposure openings, means for directing actinic light rays through said openings, a flexible belt cooperating with said openings, and stops for each of said 90 openings, said stops being adapted to move inwardly when engaged by said belt, substantially as described.

8. In a photo printing apparatus, a rotating drum having exposure openings, 95 means dividing said drum into a series of light compartments, a light source for each compartment, and means for adjusting said light sources radially, substantially as described. 100

9. In a photo printing apparatus, a rotating drum having a uniformly curved periphery formed with exposure openings, means dividing said drum into a series of 105 light compartments, each having an exposure opening, a light source for each compartment, a flexible belt cooperating with said exposure openings, and adjustable means for controlling the energization of said light sources, substantially as described. 110

10. In a photo printing apparatus, a rotating drum having a uniformly curved periphery formed with exposure openings, means dividing said drum into a series of light compartments, each having an exposure opening, a non-actinic light source for each compartment, an actinic light source for each compartment, a flexible belt cooperating with said exposure openings, and adjustable means for energizing said actinic 115 light sources for variable periods of time, substantially as described.

11. In a printing apparatus, a transparent support for the negative and printing paper, an actinic light source cooperating therewith, a negative comparison device constituting in effect a scale, and means cooperating with said device for varying the period of energization of said light source as found necessary by comparison 120 125 130

of the negative being used with said comparison device, substantially as described.

12. In a printing apparatus, a rotating drum having a series of light compartments, each provided with an exposure opening, an actinic light source for each compartment, a comparison device cooperating with said drum and constituting in effect a scale, and means cooperating with said device for energizing said actinic light sources for variable periods of time as found necessary by comparison of the negatives being used with said comparison device, substantially as described.
13. In a printing apparatus, a rotating drum having a series of light compartments, each provided with an exposure opening, an actinic light source for each compartment, a comparison device having a series of sample negatives constituting in effect a scale, and means cooperating with said device for energizing each actinic light source for varying periods of time as found necessary by comparison between the film being printed and one of said sample negatives, substantially as described.

14. In a printing apparatus, a rotating drum having a series of light compartments each provided with an exposure opening, a comparison device cooperating with said drum and constituting in effect a scale, means on said drum cooperating with said comparison device, and actinic light sources controlled by said means, substantially as described.

15. In a photo printing apparatus, a rotating drum having a series of light compartments each provided with an exposure opening, a light source for each compartment, a flexible belt extending partly around the periphery of said drum, a timing contact cooperating with said drum, said contact having successive portions thereof of varying widths, and adjustable contacts adapted to engage said timing contact during rotation of the drum, said adjustable contacts controlling the energization of said light sources, substantially as described.

16. In a printing apparatus, a rotating drum having a plurality of exposure openings, an independent actinic light source for directing light rays separately through each of said openings, an adjustable contact controlling each of said light sources, and means for indicating the proper setting of said adjustable contacts for negatives of differing characteristics, substantially as described.

17. In a printing apparatus, a rotating drum having a plurality of exposure openings, an independent actinic light source for directing light rays separately through each of said openings, an adjustable contact

controlling each of said light sources, means for indicating the proper setting of said adjustable contacts for negatives of differing characteristics, and means for automatically throwing said adjustable contacts out of circuit before each setting operation thereof, substantially as described.

18. In a photo printing apparatus, a rotating drum having a series of printing compartments each provided with an exposure opening, an actinic light source for each compartment, an adjustable contact for each light source, and a timing contact adapted to be engaged by said adjustable contacts for varying periods depending upon the setting thereof for controlling the period of energization of said light sources, substantially as described.

19. In a photo printing apparatus, a rotating drum having a series of printing compartments each provided with an exposure opening, an actinic light source for each compartment, an adjustable contact for each light source, a timing contact adapted to be engaged by said adjustable contacts for varying periods depending upon the setting thereof for controlling the period of energization of said light sources, and means for automatically throwing each of said adjustable contacts out of circuit before each setting operation thereof, substantially as described.

20. In a photo printing apparatus, a rotating drum having a series of printing compartments each having an exposure opening, an actinic light source for each compartment, a flexible belt for maintaining negatives in proper position with relation to said compartments, a curved timing contact cooperating with said drum, contacts carried by said drum adapted to engage said first mentioned contact for energizing said light sources, and means for producing a relative adjustment between said contacts for varying the period of energization of said light sources, substantially as described.

21. In a printing apparatus, a printing drum, a comparison chart cooperating therewith, said drum having a series of indicating means thereon cooperating with said chart, actinic light sources for said drum, and adjustable means cooperating with said indicating means and said comparison chart for energizing said light sources for varying periods, substantially as described.

22. In a photo printing apparatus, a rotating drum having a series of printing compartments each having an exposure opening, an actinic light source for each compartment, an adjustable contact for each compartment, and a timing contact adapted to be engaged by said adjustable contacts for varying the printing period in accord-

6
ance with the setting of the adjustable contacts, substantially as described.

23. In a photo printing apparatus, a rotating drum having an exposure opening, an actinic light source for directing light rays through said opening, an adjustable contact controlling said light source,

and means indicating the proper setting of said contact for negatives of differing characteristics, substantially as described.

In testimony whereof we have hereunto set our hands.

MICHAEL J. KOCH.
HARRY B. BOOSE.
